INDEX SLIP HOLDER

Charles Goldstein, Chicago, Ill.

Application March 7, 1934, Serial No. 714,416

4 Claims. (Cl. 40—16)

This invention relates to improvements in index slip holders having a general application in the field of filing devices, and more particularly for attachment to the margins of division cards or 5 sheets used for separating or classifying the contents of a file, in order to permit the ready removal of the indicator or index slip for the purpose of entering notations or making changes in the notations on the slip.

10 A particular application of the holder is in connection with a so-called desk portfolio frequently termed a work organizer, consisting of a flat book-like file having several bound sheets increasing in length from top to bottom and serving 15 to separate the contents under several headings. The holders for the index slips are attached to the exposed lower marginal portions of each sheet so that their indicator slips are arranged in a vertical row at the lower edge of 20 the portfolio. These holders may also be used in so-called vertical filing systems and attached to guide cards in place of or in addition to the integral index tabs with which they are ordinarily provided, and being self-contained units can be 25 placed wherever desired, thus increasing the flexibility of the system.

The novelty of the holder, however, resides in its construction as a unit apart from its application, and two of its preferred forms have been 30 illustrated in the accompanying sheet of drawings, in which

Figure 1 is a perspective view of a portfolio showing several of the holders attached to the dividing sheets thereof.

35 Figure 2 is an enlarged view of a single holder.

Figure 3 is a view in cross section of the mounted holder as taken on line 3—3 of Figure 2.

Figure 4 is a perspective view of a modified but 40 equally practical form of holder, and

Figure 5 is a view in cross section as taken on line 5—5 of Figure 4.

The portfolio or file illustrated in Figure 1 consists of stiff back and front covers 1 and 2, with 45 several sheets 3 bound between them, the lower edge 3^a of each sheet not only projecting a short distance beyond the sheet above as heretofore explained, but are reinforced and stiffened with the same binding material used in the covers. The index slip holders 4 are attached to the edges 50 3^a of the sheets, one above the other, so that the index slips held thereby are visible when the file is closed.

The holders of the form shown in Figures 1, 2 and 3 are constructed so that they can be easily 55 attached to the edges of the sheets by hand, that

is, by merely crimping one partially bent edge of the metal backing plate over the edge of the sheet, thus eliminating the need for especially designed punches for the purpose.

5 Thus as shown in Figure 2, the backing plate referred to is a strip of thin metal, say, two inches in length and one inch in width, having one longitudinal margin bent in U-shape as at 5^a along the attaching edge. The other edge is also bent and doubled over, but in the opposite direction, and within this marginal fold are anchored the free edges of a sheet of transparent sheet material such as celluloid which previously is folded double into a flat tubular strip 6, the meeting edges inserted into the fold which is then mashed 10 down flat as shown at 5^b. This tubular strip 6 of celluloid extends the length of the backing plate 5 and from the upper to the lower edges thereof, with its free edge in line with the U-shaped turned edge 5^a of the plate. To attach 15 the holder thus completed, it is only necessary to slip or hook the U-shaped edge over the edge of the sheet to which it is to be applied, and by squeezing or mashing it flat a secure attachment 20 is made.

25 The tubular celluloid strip 6 manifestly provides an open-ended sheath or pocket for the index slip 7 in the form of a strip of fairly stiff paper somewhat narrower than the pocket, so that it can slide readily into and from the same without binding, and yet be held in place. The 30 walls of the sheath are practically flat under ordinary conditions, although by pressing against its free edge the walls will bulge apart so that the slip can be readily inserted or removed. Moreover, the sheath can be bent bodily away from the 35 backing plate during the act of inserting or removing the slip, thus making the latter more accessible and easily manipulated.

The form of holder shown in Figures 4 and 5 40 is quite as satisfactory except that it costs a little more to manufacture and apply. In this form much of the plate is eliminated, the only metal part being the narrow strip 8 of double thickness 45 in which the free edges of the flatly folded celluloid sheath 9 are secured. This strip is folded longitudinally and flattened with the edges of the celluloid clamped between the folded portions, and projecting from the ends of one of the folded sections of the strip are short pointed prongs 50 8^a, 8^b initially bent at right angles thereto.

To apply this form of holder to the edge of a sheet or card, it would ordinarily require the use 55 of a special punch which would force the prongs

through and bend them in flatwise against the back of the sheet in one operation. Similarly, in making this type of folder, special dies are required for stamping out the strips, bending the 5 prongs and assembling the celluloid sheaths, whereas in the first form disclosed the making involves only simple bending and mashing operations which can be carried out with the use of hand tools or inexpensive forms applied to a 10 standard punch press.

For simplicity of manufacture and application, the first form has its advantages, although in other respects the prong-attached type may be preferred in that it is lighter and neater in appearance and can be attached without regard to the distance of the point of attachment from the edge of the sheet or card. Thus for example, the prong-attached holder can be placed so that the sheath projects beyond the edge of the sheet 15 or card to which it is attached, and thus becomes a tab, whereas the crimped edge applied type of Figure 2 is confined to one position of attachment, although it is apparent that the width of the plate could be varied to locate the attaching 20 edge at different distances from the anchored edge of the sheath if desired.

And in this connection I am aware that celluloid tabs with removable index slip-holding pockets have been applied to guide cards for use in 25 vertical filing systems, but in these instances the tab is an integral part of the card, whereas the holders herein disclosed are complete units which may be applied whenever and wherever needed, and, therefore, have the advantage of a general 30 utility aside from the simplicity of construction, convenience in manipulation and accessibility of 35

the index slip for removal from or insertion into the transparent sheath.

Having set forth a preferred embodiment of my invention, but without any intention of limiting its application to any specific field,

I claim as my invention:

1. An index slip holder comprising a flat tubular sheath of a transparent sheet material having open ends to receive an index slip, and a metal strip having a portion folded double and clamped 10 along one of the longitudinal edges of the sheath and another portion for attaching the same to a sheet or card.

2. An index slip holder comprising a metal strip adapted for attachment along one edge to a sheet 15 or card, and an index slip-receiving pocket consisting of a sheet of transparent material folded double into flattened tubular form and its meeting edges clamped between a folded-over marginal portion at the opposite edge of said strip.

3. An index slip holder comprising a metal plate having one of its longitudinal edges bent in U-shape to provide a clip to engage the edge of a sheet or card, and a slip-receiving sheath consisting of a sheet of transparent material folded 20 double into flat tubular form and its meeting edges secured along the opposite edge of said plate.

4. An index slip holder comprising a metal plate having one of its longitudinal edges bent in U-shape to provide a clip to be fastened to the 25 edge of a sheet or card, and a slip-receiving sheath consisting of a sheet of transparent material folded double into flat tubular form and its meeting edges clamped between a folded-over marginal portion of the plate at its opposite edge.

CHARLES GOLDSTEIN.
